UNITED STATES PATENT OFFICE.

ARTHUR H. WALLIS, OF BASINGSTOKE, ENGLAND.

ENGINE-STARTER.

SPECIFICATION forming part of Letters Patent No. 439,449, dated October 28, 1890.

April 30, 1890. Serial No. 350,045. (No model.) Patented in England December 19, 1889, No. 20,443, and in South African Republic March 28, 1890, No. 166.

To all whom it may concern:

Be it known that I, AERTHUR HERBERT WALLIS, engineer, of North Hants Iron Works, Basingstoke, in the county of Hampshire, England, have invented a new and useful Improvement in Starting and Stopping Apparatus for Compound-Engines, (for which I have obtained patent in South African Republic, dated March 28, 1890, No. 166, and in Great Britain by an application for patent, which patent, when granted, will bear date December 19, 1889, No. 20,443,) of which the following is a specification.

As compound engines are usually arranged, steam, after performing work in one cylinder, exhausts therefrom into a reservoir, whence it supplies another cylinder at lower pressure, and this may be repeated three or more times. It is difficult to effect the stopping and starting of an engine of this kind, because, in the case of stoppage, although the supply to the high-pressure cylinder may be cut off, the reservoir or reservoirs go on supplying the low-pressure cylinder or cylinders, keeping the engine in motion, and in the case of starting, although the high-pressure cylinder may be supplied, there is no supply to the low-pressure cylinder or cylinders.

My invention relates to means of overcoming these difficulties, which I effect in the following manner: I provide shut-off valves for the slide-jackets of the several cylinders so arranged that they are simultaneously opened or closed by one action, and I furnish the reservoir, or each reservoir, if there are several of them, with a supply-pipe governed by a reducing-valve so adjusted that the reservoir is supplied with live steam only when the pressure in the reservoir is below a certain minimum sufficient for acting in the low-pressure cylinder connected to the reservoir. Thus by the one action of closing the valves I can shut off steam from all the cylinders, so causing immediate stoppage of the engine, and as the reservoirs are always, during working, charged up to the minimum pressure required by the one action of opening the valves, I admit steam to all the cylinders, causing the engine to start.

Figure 1 of the accompanying drawings is a part side view, and Fig. 2 is an end view, of the cylinders of a compound two-cylinder en-

gine to which my invention is applied. Fig. 3 is a transverse section of the cylinders through the high-pressure slide-valve, and Fig. 4 is a similar section through the low-pressure slide-valve. Figs. 5 and 6 are vertical sections on planes at right angles to one another; and Fig. 7 is a sectional plan showing, on an enlarged scale, a convenient form of reducing-valve which I employ.

I provide sluice-valves A and B or other suitable stop-valves by which I can simultaneously cut off the steam-supply to the high and the low pressure cylinders, respectively, the stems of these valves being both connected to arms of one rocking-shaft C, so that on moving this rocking-shaft by a lever D, both valves A and B are simultaneously closed or opened for the purpose of stopping or starting the engine.

I provide a reducing-valve E, Fig. 3, which may be of the construction shown in Figs. 5, 6, and 7. It has two valves on the stem of a piston Q, which is pressed down by a loaded lever, so that when these valves are unseated there is communication between two branches F and G. The branch F communicates with the space H of the high pressure slide-jacket, which space, when the valve A is open, is supplied with steam direct from the boiler by the pipe P. The branch G communicates with the reservoir space R, which receives the exhaust from the high-pressure cylinder, and which when the valve B is open supplies the space L of the low-pressure slide-jacket. The apparatus operates as follows: By moving in one direction the lever D both the valves A and B are closed, cutting off steam from the slide-jackets of both cylinders, and the engine is stopped. When it is desired to start again, both the valves A and B are simultaneously opened by moving the lever D in the opposite direction, and if the reservoir R should at that time contain steam at pressure sufficient for the low-pressure cylinder the engine is started; but should the pressure in R have become too low or tended to become too low then the reducing-valves E operate, admitting steam from the slide-jacket H to the reservoir R, thus maintaining in R the pressure determined by the adjustment of the reducing-valve E. This pressure is adjusted by proportioning the load on the lever to the

area of the piston Q, so that the valves attached to that piston open only when the pressure upward on the piston Q, which is the pressure in R, is less than the load on the 5 piston downward. Obviously, instead of a weight the piston Q might be loaded by a spring or by the pressure on another piston connected to it.

I prefer to provide in addition to the reducing-valve E a check-valve M, closing a passage from F to G, so that when, although steam is shut off, the momentum of the fly-wheel continues the movement of the engine, causing a pumping action in the cylinders, 10 steam can pass from the reservoir R to the high-pressure slide-jacket, thus maintaining the high-pressure slide-valve in equilibrium, and so preventing it from being forced away from the facing.

Ordinary engines usually have a single 15 shut-off valve, which is for the high-pressure supply, and as there is steam coming from the high-pressure cylinder and supplying the low-pressure cylinder, it is impossible to stop the engine as rapidly as is desirable, for though 20 the high-pressure supply is cut-off there is sufficient steam in the reservoir to keep the low-pressure cylinder moving. In consequence of the lack of means to shut off the 25 steam-supply from both cylinders simultaneously serious accidents have occurred when such engines are applied for the winding in mines, because if the engine cannot be promptly stopped when the cages reach the 30 top there is a break-down. By providing each cylinder with a shut-off valve and connecting such valves to one lever the stoppage of the engine can be rapidly effected by closing the 35 valves, and there being always supply of steam to the low-pressure cylinder admitted 40 to its reservoir by the reducing-valve, the engine can be quickly started by opening the two valves.

Although I have shown my invention applied to a compound engine having only two 45 cylinders, obviously when there is a greater

number of cylinders the apparatus may be repeated for each successive pair. For example, when there are three cylinders, with a reservoir between the first and second and a 50 reservoir between the second and third, I provide three shut-off valves, one for each cylinder, connected to one lever, and two reducing-valves, one between the slide-jacket of the first cylinder and the reservoir, which its 55 exhaust supplies, and one between the slide-jacket of the second cylinder and the reservoir supplied by its exhaust. The reducing-valve in each case operates automatically, supplying the reservoir with steam when 60 steam is required.

Reducing-valves have heretofore been proposed for supplying the reservoir of the low-pressure cylinders of compound engines; but my invention resides in the combination, with 65 a reducing-valve, of shut-off valves simultaneously operated for both cylinders.

Having thus described the nature of my invention and the best means I know of carrying the same into practical effect, I claim— 70

In combination with the cylinders and intermediate reservoirs of a compound engine, shut-off valves, one for each cylinder, connected to one lever or motor, by which they are simultaneously opened or closed, and 75 an adjustable reducing-valve in communication from the supply of each cylinder to the reservoir supplied by its exhaust, substantially as and for the purpose herein set forth.

In testimony whereof I have signed my 80 name to this specification, in the presence of two subscribing witnesses, this 16th day of April, A. D. 1890.

ARTHUR H. WALLIS.
